UNITED STATES PATENT OFFICE.

PERCY PRESTON, OF ARDMORE, OKLAHOMA.

ORGAN.

Application filed October 17, 1922. Serial No. 595,193.

To all whom it may concern:

Be it known that I, PERCY PRESTON, a citizen of the United States, residing at Ardmore, in the county of Carter and State of Oklahoma, have invented a new and useful Organ, of which the following is a specification.

This invention relates to improvements in organs and more particularly to a pipe tone pedal base for use in connection with a combination piano and organ, one of the objects of the invention being to provide a key action which can be moved into and out of operative relation with the organ mechanism without the necessity of first cutting away portions of the casing of the instrument.

Another object is to improve upon the means for controlling the sounding of the reeds.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawing the preferred form of the invention has been shown.

In said drawings, Figure 1 is a transverse section through the structure. Fig. 2 is a section through the mutes shown in open position.

Referring to the drawing by characters of reference 1 designates a piano key having a projection 2 adapted to engage and depress a lever 3. This lever is connected by a tracker 4 to a valve 5 yieldingly supported by a spring 6. This valve serves to control the flow of air between the vacuum chest and the port 7 to pneumatic 18 hereinafter referred to. Port 8 is the exhaust and is connected to the organ bellows at any convenient point. The vent 9 is the exhaust and intake of the said pneumatic 18 and is a part of port 7. It is always open at one end, depending on the position of the key. A tracker 11 keeps valves 5 and 10 in proper relative positions and is housed in vent 9.

It will be noted that the projection 2 on the key 1 extends under the wall of the

case A of the piano so that the key can be slid into or out of operative relation with the lever 3 and it becomes unnecessary to cut holes into the case or otherwise mutilate it.

The vacuum chest of the reed board has been indicated at 12, this chest being small enough to act as a tone qualifier. A reed has been indicated at 13 and the reed cell has been indicated at 14. This cell is adapted to be closed by a valve 15 loosely mounted on retaining pins 16. One end of the valve is hingedly connected by a leather strip 17 or the like to the bottom of a pneumatic 18, this bottom portion of the pneumatic being movable while the upper portion is stationary as shown at 19. An air passage 20 extends through the stationary portion of the pneumatic and is connected by a pipe 21 to the port 7. The resonance chamber has been indicated at 22 and the top of this resonance chamber is shown at 23. In this top is provided a port 24 through which air is allowed to pass to the reeds. A mute is hingedly mounted on the top 23, as shown at 25, it being designed to operate this mute by a pneumatic not shown. A "double mute" 26 is hingedly connected to the mute 25, this double mute remaining in contact with the top 23 when the mute 25 is opened, thus to make a soft pedal stop. It is designed to utilize a loud pedal stop to open both of the mutes 25 and 26 to full capacity.

The pneumatic employed for this purpose has not been shown as it is believed the construction will be obvious to anyone skilled in this art. A shutter or muffler 27 is hingedly connected to the top of the chamber 28 in which the mutes are mounted and this shutter is adapted to be operated by a pneumatic, not shown, for producing the "swell." The vacuum chest 12 is of course in communication with the main air chest and for the purpose of convenience an opening for this purpose has been indicated at 29.

What is claimed is:—

1. The combination with a resonance chamber having an opening therein, and a chamber above the resonance chamber, of a shutter for closing the upper chamber, a mute movably mounted within the upper chamber for closing the opening in the resonance chamber, and a double mute hingedly connected to said mute.

2. In an organ the combination with a

resonance chamber, a reed cell, and a vacuum chest, of a reed interposed between the chest and the reed cell, a valve for closing the reed cell, a pneumatic for actuating the valve, means opening into the vacuum chest for maintaining communication with a main air chest, and key operated means for controlling the operation of the pneumatic.

3. In an organ the combination with a vacuum chest, means for maintaining communication between the vacuum chest and the main air chest, a reed cell, a reed inter-

posed between said cell and the vacuum chest, and a resonance chamber, of a valve normally closing communication between the reed cell and the resonance chamber, a pneumatic for operating the valve, and key controlled means for actuating the pneumatic.

In testimony that I claim the foregoing as my own, I have hereto affixed my signature.

PERCY PRESTON.
